Wm. S. Worthington

Perforated Banner.

PATENTED

NOV 16 1869

A. E. Gale
C. A. Graves

Wm. S. Worthington, by his Atk L. D. Gale:

United States Patent Office.

WILLIAM S. WORTHINGTON, OF NEWTOWN, NEW YORK.

Design No. 3,755, dated November 16, 1869.

DESIGN FOR A PERFORATED BANNER.

The Schedule referred to in these Letters Patent and making part of the same.

Be it known that I, WILLIAM S. WORTHINGTON, of Newtown, county of Queens, and State of New York, have invented certain new and useful Devices in the Form and Configuration of Show-Cards, Signs, Banners, and their equivalents; and I do hereby declare that the following is a full and exact description of the same, reference being had to the accompanying drawings, and references thereon, which make a part of the description.

These designs, which are claimed as designs in this application, are made of perforate goods, such as rubber-cloth, tin, wood, rubber, sheet-brass, copper, or any other equivalent material which is readily perforated, in order to give the design the benefit of a translucent or a transparent sign, in which the lettering-design or symbol may be shown as opaque, while the ground-work of the picture is open-work, made by perforating the ground with holes, as shown.

The object of this improvement is, to make a banner that will hang still and quiet, and can be read easily.

The advantage, for signs and show-cards for the inside of stores, is, they do not obscure the vision, as

the interstices permit a clear view of all the goods beyond them, which is a great desideratum.

A wire frame can be put around the edge, to make it firmer.

Strips, not perforated, can be left for lettering on, or the letters made of other material, and fastened on the sheet.

I wish it to be distinctly understood, that I do not claim a design for banners, flags, or show-cards, by sewing two pieces of canvas, one on each side of a sheet of netting, and lettering on them.

Having described the nature of the invention, and the mode of using the same, I will state that I do not claim the making of a show-card, sign, banner, or other similar device; but

What I claim as my invention, and desire to secure by Letters Patent, is—

The form and configuration of a perforated banner, sign, show-card, or their equivalents, substantially as described, and represented in the drawing.

Witnesses: WM. S. WORTHINGTON.

EDM. F. BROWN,
L. D. GALE.
